SEWING MACHINE

George Sauer, Berwyn, Ill., assignor to Union Special Machine Company, Chicago, Ill., a corporation of Illinois

Application July 2, 1940, Serial No. 343,513

12 Claims. (Cl. 112—200)

This invention relates to sewing machines; and it has reference more particularly to flat bed chain stitch sewing machines useful for example, in closing the mouths of successively fed filled bags either by stitching alone or by stitching with concurrent application of reinforcing elements along the line of the seam.

Machines of the kind referred to are ordinarily provided with feeding mechanisms whereof the rocker for directly imparting to and fro or feeding movements to the feed bar is disposed rearward of the point of stitch formation, and actuated by means inward of and along the feed bar from a longitudinally extending rotary or feed shaft below the work support. Such machines are moreover ordinarily provided with severing mechanism by which free connecting portions of the stitch chain or the stitch chain and the tape are cut between the successive articles. In machines thus organized, it was necessary to place the chain cutting or the chain and tape cutting instrumentalities either to the rear of the feed bar remote from the region of stitch formation, or to crowd them into small, obstructed and inadequate intervening spaces where access to them for the purposes of inspection, adjustment or replacement was difficult and time consuming.

The chief aim of my invention is to overcome the above drawbacks, which objective I realize in practice as hereinafter more fully disclosed, by disposing the feed rocker forward of the point of stitch formation so that ample space is afforded immediately to the rear of the feed dog for placement of at least one of the cutting instrumentalities where the latter are more readily accessible; and by disposing the elements for actuating the feed rocker at the opposite end of the feed shaft where they too are more readily accessible for inspection and adjustment.

Another aim of my invention is to attain greater compactness in feeding mechanism having the above attributes which desideratum I also realize as hereinafter more fully disclosed by placing the feed bar in the plane of the needle in a position where the looper may operate above it or to the needle side of it—depending upon whether the machine is used in horizontal position or in vertical position, drive end up as is usual in bag closing—and providing it with an aperture for passage of the needle through it.

Another aim of my invention is to attain the foregoing advantages in a sewing machine wherein the frame has a hollow base (as considered with the machine in horizontal position) which contains the feeding mechanism and parts of the

severing mechanism; a hollow needle arm supporting standard which is oil tight and contains drive mechanism whereby the lower or feed shaft is connected to an upper or needle drive shaft, and an isolated chamber beyond the standard in which the elements connected to said lower or feed shaft for actuating the feed rocker are housed.

Other objects and attendant advantages will appear from the following detailed description of the attached drawings wherein Fig. 1 is a view in vertical longitudinal section of a sewing machine conveniently embodying my invention with the machine shown in horizontal position.

Fig. 2 shows the left hand end elevation of the machine with the front cover plate of the needle head removed to expose the parts at the interior.

Fig. 3 is a horizontal section of the machine taken as indicated by the angled arrows III—III in Fig. 1.

Fig. 4 is a fragmentary view partly in elevation and partly in section taken as indicated by the angled arrows IV—IV in Fig. 3.

Fig. 5 is a view corresponding to Fig. 4 showing, in open position, the severing means by which the thread chains between successive bags are cut.

Fig. 6 is a diagrammatic view in plan further showing the action of the stitch chain severing means.

30 Figs. 7 and 8 are detail views looking as indicated respectively by the angled arrows VII—VII and VIII—VIII in Fig. 3.

Figs. 9, 10 and 11 are views corresponding to Figs. 1—3 showing another embodiment of my invention.

Fig. 12 is a fragmentary view in plan looking down upon the machine bed as indicated by the angled arrows XII—XII in Fig. 9; and

Fig. 13 is a cross sectional view of the machine 40 through the machine base taken as indicated by the arrows XIII—XIII in Figs. 9, 11 and 12.

In the description which follows and in the claims, the relation of the parts is defined with respect to the horizontal position of the machine, 45 which position has been chosen merely for convenience of illustration, although, as has been pointed out hereinbefore, the machine may be used in vertical position with its drive end uppermost.

50 The machine illustrated in Figs. 1—8, to which particular reference will be had for the time being, is designed for closing the mouths of bags solely by means of a stitch chain, and to sever the connecting portions of the chain between successive bags. As shown, the frame of the ma-

chine is formed as an integral structure with a hollow bed or base 15 whereof the top and bottom, rear and front walls are respectively designated by the numerals 16, 17, 18 and 19, said base being open at the left hand end, see Figs. 1, 2 and 3. Rising from the base 15 at the right hand end, is a hollow standard 20 from which extends horizontally at the top, a hollow arm 21 with a hollow head 22 at its free end, said head having a removable end cover 23. From Fig. 1 it will be noted that in accordance with my invention, the outer wall 24 of the standard is continued downwardly as at 25 to form the right hand end wall of the base 15, and that the inner wall 26 of said standard is likewise extended downward as at 27 to form a partition crosswise of said base. Also as shown in Fig. 1, the inner wall 26 of the standard 20 is continued upwardly to form a partition 28 crosswise of the hollow overhanging arm 21, and that another crosswise partition 29 spaced from the partition 28 isolates the hollow 30 of the head 22 from the central chamber 31 within said arm. Extending lengthwise through the overhanging arm 21 near the bottom thereof is a rotary shaft 32 which is journalled in bearing sleeves 33 and 35 set respectively into the partitions 28 and 29. The shaft 32 also has journal support in a bearing sleeve 36 set into a boss 37 formed on the outer wall 24 of the standard 20 and extends to the exterior for connection thereto of a combined hand and belt wheel 38 whereby the machine can be operated either manually or by power.

Confined to up and down movement in guide bushings 40 and 41 set into the top and bottom of the head 22 is a bar 42, which carries a needle 43 at its lower end and which is reciprocated endwise, through a pitman 45, from a balanced crank member 46 secured to the left hand end of the shaft 32 within the hollow of the head. From Fig. 2 it is to be especially noted that the bushing 40 is of such length that the upper end of the needle bar 42 is completely sheathed when elevated to the fullest extent. This provision serves as a safeguard against injury to the operator when the machine is used in vertical position.

Cooperative with the needle in stitch formation within the base, is a looper 47, see Figs. 2 and 3. As shown, the looper 47 is secured to the upstanding arm 48 of a looper carrier 49 which is mounted for oscillatory movement about a laterally-extending pin or stud 50 on a collar 51 secured to a horizontal rock shaft 52 at the left hand end. The rock shaft 52 is journalled in spaced bearings 53 and 55 upstanding from the bottom 17 of the base 15, and affixed to it in the interval between the bearings 53 and 55, is a laterally extending arm 56, which, through a strap rod 57, is connected with an eccentric 58 on a rotary shaft 59 extending horizontally through the base of the machine. By the means just described, the looper 47 is given its needle avoiding movements. Through a train of intermeshing spur gears 60, 61 and 62 within the standards 20, the shaft 59 is driven in unison and in the same direction as the upper shaft 32. As shown in Figs. 1 and 3, the lower rotary shaft 59 is journalled in set bearings 65 and 66 respectively in the partitions 25 and 27 and also has journal support in bearing bosses 67 and 68 upstanding from the bottom 17 of the base. Loop taking movements are imparted to the looper 47 through means which includes a horizontal link 69 connected at one end to the upstanding arm 48 of the looper

carrier 49 and at the other end to an upstanding arm 70 whereof the fulcrum hub is rotatively free on a crosswise shaft 71 which is fixedly held at its opposite ends in spaced lugs 72 and 73 upstanding from the bottom 17 of the base 15. Affixed to the rock shaft 71 intermediate the bosses 72 and 73 is a horizontal crank arm 75, which, through a short vertical pitman 76, is connected to a crank 77 on the rotary shaft 59.

The improved feeding mechanism of the machine includes a feed dog 78 whereof the toothed portions operate through slots in a removable throat plate 79 set into the top wall 16 of the base. As shown in Fig. 2, the feed dog 78 has its shank 80 secured with capacity for vertical adjustment to the horizontal portion of a carrier bar 81 by means of a screw 82. In accordance with my invention, the feed bar 81 is fashioned to angular configuration with its horizontal portion in the plane of the needle 43 in the line of feeding, which is apertured as at 83 for passage of the needle 43 through it, and a vertical portion which extends downwardly of the rear end of said horizontal portion. At its bottom end, the pendant portion 84 of the feed bar 81 is pivotally connected to the lower end of a link 85 whereof the upper end is engaged with a crank 86 at the left hand or distal end of the lower rotary or feed shaft 59. Through this means, up and down or lift movements are imparted to the feed dog 78. It is to be particularly noted from Fig. 2 that the toothed portion of the feed dog 78 extends rearwardly of the direction of feeding and overreaches considerable of the horizontal portion of the feed bar 81, and that the looper 47 operates above the feed bar in the interval between the latter and the overreaching portion of the feed dog. At its front end, the horizontal portion of the feed bar 81 is pivotally connected to an upstanding arm 87 on the distal end of a tubular rock shaft 88 which extends lengthwise through the base 15 in parallel relation to the rotary shaft 59 forwardly of the latter as considered with regard to the direction of feeding. At its left hand end the rock shaft 88 is journalled in bearing lugs 89 and 90 projecting inwardly from the front wall 19 of the base, and at its right hand end in bearings 91 and 92 set into the partitions 25 and 27. Due to the construction and arrangement of the feeding mechanism insofar as it has been disclosed, a clear space is left to the rear of the vertical portion of the feed bar 81 for the accommodation of a stitch chain severing mechanism which will presently be described. As shown in Figs. 1 and 3, the right hand ends of the shafts 59 and 88 extend beyond the bearings 65 and 91 into a lateral recess 93 formed in the outer wall 25 of the standard 20, said recess being closed by a removable cover plate 94. Secured to the rock shaft 88 within the recess 93 is a rearwardly extending horizontal arm 95, which, through a short vertical pitman 96 is connected to an adjustable crank pin 97 on the right hand end of the rotary shaft 59. The parts just referred to constitute the means whereby horizontal to and fro or feed movements are induced in the feed dog 78, said parts being readily accessible upon removal of the cover 94, for the purposes of regulation to vary the feed stroke of said dog.

Incident to performing its feed strokes, the feed dog 78 is opposed by a presser foot 100 whereof the front end is inclined upwardly and curved as at 101 to facilitate entry of the leading edges of the bag mouths beneath it. As

shown, the presser foot 100 is pivotally connected at 102 to a shank member 103 at the lower end of the vertical presser bar 105 extending upwardly through a guide bushing 106 at the bottom of the needle head 22 into the interior of said head. The presser bar 105 is subject to the action of a leaf spring 107 enclosed within the overhanging arm 21. As shown, the spring 107 is apertured at its right hand end to engage the reduced top end of a pylon 108 upstanding from a transverse web 109 within the arm 21 intermediate the partitions 28 and 29, and its outer end is bifurcated to fit over a stirrup-like member 110 resting over the top of the presser bar 105. The pressure of the spring 107 is regulatable by means of a screw 111 which is threaded into a boss 112 at the bottom of the overhanging arm 21. The presser foot 100 is controllable by means including a rock shaft 113 which extends lengthwise of the overhanging arm 21 and which is journalled in the partitions 28 and 29. Affixed to the end of the rock shaft 113 within the needle head 22 is a horizontal finger 115 which underreaches a collar 116 secured to the presser bar 105 near the upper end. Extending outward through a slot 117 in the rear side wall of the overhanging arm 21 is a lever 118, which, at its inner end, is clamped to the rock shaft 113 within the chamber 31 by means of a screw 119. A torsion spring shown at 120 in Fig. 2 with one end thereof engaging the finger 115 from above tends to keep the lever 118 normally in the horizontal position shown with its upper edge bearing against the corresponding edge of the slot 117. Thus, as the lever 118 is depressed, the finger 115 will engage the collar 116 and thereby cause the presser foot 100 to be elevated for convenience of initially inserting the work therebeneath. By means of a link rod 121, the lever 118 may be connected either to an actuating knee press or foot treadle (neither illustrated) as desired. From Fig. 1, it will be noted that the hub 122 of the lever 118 is extended axially and has a wing 123, which, when said lever is operated, tends to push the stem 124 of a spring thread tensioning device 125 for the needle thread within the chamber 31 of the overhanging arm 21, thereby to relieve said thread concurrently with the lifting of the presser foot. The parts within the overhanging arm 21 are rendered accessible upon retraction of the cover 126 at the top of the chamber 31.

As previously stated, the machine is designed for stitching articles such as filled bags B whereof the open mouths are advanced in succession across the work support 16 as shown in Fig. 6, by the feed dog 78, and chain-stitched by the needle 43 and its cooperating looper 47. For the purpose of severing the portions of the stitch chain C between succeeding bags B (Fig. 6) I have provided an improved shearing mechanism, which, see Figs. 3-6, comprises a pair of blades 127, 128 arranged crosswise of the direction of feeding immediately to the rear of the vertical pendant portion of the feed bar 81. The blade 127 is adjustably secured to the rear wall 18 of the machine base, at the left hand thereof by a screw 129; while the blade 128 is similarly secured by means of a screw 130 within the slotted top of the vertical arm 131 of an angular lever 132. The horizontal arm 133 of the lever 132 is fast on a rock shaft 134 whereof the ends are journalled respectively in the end wall 18 and a bearing lug 135 upstanding from the bottom 17 of the base 15 within the hollow of the lat-

ter. A helical spring 136 surrounding the shaft 134 bears against the hub of the lever 132, see Fig. 2, to yieldingly maintain the moving blade 128 at all times in shearing relation with the fixed blade 127. As shown in Fig. 5, the blade 128 has an extension 137 beyond its cutting edge 138, and against which the cutting edge 139 of the blade 127 bears for maintenance in alignment with the cutting edge 139 of the stationary blade. Directly over the region of meeting of the cutting blades 127, 128, the work supporting plate 19 has a slot 140 in the line of feeding into which the connecting thread chain C, between successive bags, is drawn incident to manipulation of the bags in the machine, and is interrupted by the extension 137 of the moving blade 128 and between the cutting edge of the latter and that of the fixed blade 127, so that the chain is severed upon the next actuation of the cutting mechanism. In the region of the cutting mechanism, the top of the rear wall 18 of the base 15 is thickened somewhat as at 141 (Figs. 2 and 3) and is provided with a slot 142 which registers with the slot 140 in the work support and which is sloped as at 142a (Fig. 2) to act after the manner of a chute to discharge the cut portions of the thread chain C from the machine. As shown in Figs. 3 and 6, the slots 140 and 142 are both rounded to facilitate entry of the thread chain. The movable knife blade 128 is actuated from an eccentric 143 on the rotary shaft 59 within the hollow of the base 15 in the interval between the looper rocker eccentric 58 and the bearing lug 67, through a pendant strap link 144 whereof the lower end is connected to a ball stud 145 at the corner or angle of the lever 132 which carries said movable blade.

By reason of the compact arrangement of the feed dog and its rocker, and in view of the remote disposal of the feed movement inducing elements at the driving end of the machine, ample space is afforded at the left hand end of the machine base at the rear for accommodation of the cutting elements of the chain severing mechanism. Moreover, since the left hand end of the base is open, as shown in Figs. 1-3, both the feed dog and the cutting elements are readily accessible for inspection, adjustment or replacement. In practice a removable cover (not shown) is preferably provided for the open left hand end of the machine base.

The aforescribed construction of the machine frame and feeding mechanism lends also itself to the incorporation of trimming mechanism and tape applying and severing mechanism of the kind featured in a copending patent application Serial No. 251,298 filed by me on January 17, 1939. In Figs. 9-13, I have shown a sewing machine so organized, which, except as hereinafter particularly pointed out, is like that shown in Figs. 1-8, and accordingly in order to obviate repetitive description, the corresponding parts in the latter illustrations are identified with the same reference numerals previously employed, except for the addition in each instance of the letter "a" for convenience of more ready distinction.

As shown in Fig. 10, the presser foot 100a is longitudinally slotted at the bottom as at 150 to serve as a guide for a reinforcing strip or tape T which is to be applied crosswise of the mouths of the bags at one side, the tape being first led through a vertical supplemental guide 151 supported at the front side of the needle head 22a enroute from a source of supply, not

illustrated. A second reinforcing strip or tape T' for application to the opposite sides of the bag mouths is guided through a slot 152 formed in the throat plate 79a, as shown in Figs. 10 and 12, after having traversed another supplemental guide 153 secured to the base 15a of the machine at the front side 19a thereof. Affixed to the feed bar 81a of which the horizontal portion is extended rearward as at 155 in the direction of feeding, is a supplemental feed dog 156; and cooperating with this supplemental dog to assist in holding the bag material and the strips T, T' to the work support during the stitching, is a supplemental presser foot 157. As shown, the supplemental presser foot 157 is pivotally connected to the outer end of a horizontal arm 158 (Fig. 12) fulcrumed on a stud 159 which projects laterally from the forwardly-reaching arm 160 of a fixed bracket 161 bolted to the top of the machine base 15a. A finger spring shown at 162 in Fig. 12 presses upon the arm 158 and thus serves to urge the supplemental presser foot 157 toward the machine base over the region of the supplemental feed dog 156. By the mechanisms thus far described, the two reinforcing tapes T, T' are concurrently applied crosswise of opposite faces of the collapsed mouths of the bags successively advanced beneath the presser feet 100a, 157 by the action of the feed dogs 78a, 156, and said bag mouths closed by a line of chain stitches formed centrally of the tapes T, T'.

The machine also involves means for trimming off the excess material at the bag mouths, which means includes a vertically reciprocating cutting blade 163 with an inclined saw edge opposed to the direction of feeding, said blade passing down through a clearance slot (not shown) in the pressed foot 100a to one side of the plane of the presser bar 105a and also through a registering slot 165 in the throat plate 79a, see Fig. 12, to shear against one side of the latter slot. The trimming is thus effected along a line which coincides with the outer edges of the two reinforcing strips T, T'. As shown in Figs. 9 and 10, the movable knife blade 163 is secured to a head 166 at the lower end of a vertical slide rod 167 which is confined to up and down movement in a guide bracket 168 at the bottom of the needle head 22a. The slide rod 167 is actuated, through a pitman 169, from an eccentric 170 affixed to the needle actuating shaft 32a of the machine immediately adjacent the counterbalanced crank member 46a, said pitman extending through a clearance opening 171 in the sloping bottom portion of the needle head.

The incorporated mechanism for severing the stitch chain and the strips T, T' beyond opposite side edges of the bags, includes a stationary blade 172 whereof the cutting edge extends crosswise of the interval between the main and auxiliary feed dogs 78a, 156 and the corresponding main and supplemental presser feet 100a, 157, and is exposed within a transverse slot 173 in the throat plate 79a. As shown in Figs. 10, 11 and 12, the stationary blade 172 has a laterally-turned pendant attaching or shank portion 175, which, by means of a cap screw 176, is secured to a bracket 177 reaching inwardly from the rear side wall of the machine base 15a. With the stationary blade 172 cooperates a movable blade 178 at the outer end of an arm 179 fulcrumed on a shaft 180 which is fixedly supported at opposite ends in spaced bosses 181, 182 of the bracket 161 hereinbefore referred to, see Fig. 12. The movable blade 178 is normally held in elevated retracted

position by the action of a coiled tension spring shown at 183 in Fig. 12 which tends to draw the arm upwardly. Free on the shaft 180 within a bifurcation at the fulcrum end of the knife arm 179, is a rocker 185 which is constantly oscillated as a consequence of the connection of an arm 186 thereon by a link 187 with an eccentric 188 on the shaft 59a, said link passing downwardly through a clearance opening in the top 16a of the machine base 15a. Arranged to coact with the rocker 185 is a coupling member in the form of a latch dog 190 which straddles the knife arm 179, said dog having pendant ears which extend downward of opposite sides of said arm and freely engage the opposite ends of a pivot pin 191 passing through the arm, see Figs. 9 and 12. A compression spring 192 exerts upward pressure upon the latch dog 190 to hold the latter elevated with its pawl end 193 normally retracted out of the path of a notched projection 195 on the constantly oscillating rocker 185. Opposing the action of the spring 192 is a lighter spring 196 in compression between a tail projection 197 of the latch dog 190 and a corresponding projection 198 on a trigger element 199, which is freely fulcrumed on the pin 191, at one side of the knife arm 179 in contiguous relation with the corresponding ear of the latch dog 190. As shown in Fig. 9, the trigger element 199 has a horizontal projection 200 opposite the projection 198 which abuts a vertical stop screw 201 adjustable in the dog 190. The trigger element 199 also has a depending feeler finger 202, which, by the action of the spring 196 upon said element, is yieldingly urged toward a control member 203 free on the shaft 180 adjacent the knife arm 179, see Fig. 9. As shown, the control member 203 has an end surface 205 which is tangential to an arc struck from the axis of the shaft 180, and provided with a sharp medially disposed cam projection 206. The control member 203 is moreover formed with a rearwardly extending arm 207 (Fig. 12) which, by means of a vertical link 208, is pivotally connected to the rear end of a detector arm 209, the latter being fulcrumed on the stud 159 on the arm 160 of the bracket 161, in the interval between the arm 158 of the auxiliary presser foot 157 and said bracket arm. Adjustably secured to the free end of the detector arm 209 is a detector 210 which has the form of a shoe and which is undertraveled by the collapsed mouths of the bags successively passed through the machine. The bottom edge of the detector 210 is yieldingly depressed normally into a slot 211 in the throat plate 79a by a coiled finger spring 212 which underreaches the detector arm 209 rearwardly of its fulcrum.

The operation of the severing mechanism embodied in the machine of Figs. 9-13 is fully described in the copending application to which reference is made hereinbefore, and it is therefore deemed unnecessary to repeat it here, since, per se, it does not constitute any part of the present invention. In the present connection, however, it is important to observe that by reason of the novel construction and arrangement of the feed mechanism, ample room is afforded in the left hand end of the machine base for the accommodation of the lower knife 175 of the tape cutting mechanism as well as for the bracket 177 by which said knife is supported, and that the securing screw 176 is readily accessible when removal of said knife becomes necessary for re-sharpening or replacement.

Attention is also directed to the fact that in both the machines which have been exemplified, the construction and arrangement of the feeding mechanism actually makes it possible to reduce the width of the machine base (see Figs. 3 and 11) at the left hand end notwithstanding the provision of more ample room for the accommodation of the cutting element of the chain and tape severing mechanisms rearward of the feed dog in the line of feeding. Another feature of great practical importance is that the machine frame lends itself to either of the two exemplified forms of severing mechanisms without entailing any changes either in the feeding mechanism, the needle actuating mechanism, or the presser foot and tension control. While either machine may be used in the horizontal position in which position it is herein shown for convenience of illustration; it is more often suspended in vertical position from its standard end (e. g. right hand end in Fig. 1) when employed for closing the mouths of filled bags.

Having thus described my invention, I claim:

1. In a sewing machine, a work support; a reciprocating needle movable through the work support; a feed bar of right angle configuration in the plane of the needle with a portion aligned in the direction of feeding and extending forwardly of the needle, and a perpendicular terminal portion immediately rearward of the needle in the direction of feeding; a rocker connected to the front end of the feed bar for imparting longitudinal feed movements to the bar; means connected to the perpendicular portion of the bar for imparting lift movements to the bar; and means cooperative with the needle in stitch formation including a looper which moves in an orbit at the needle or work support side of the feed bar, and a carrier arm for the looper movable laterally of the feed bar at the side thereof remote from the work support.

2. In a sewing machine, a work support; a reciprocating needle movable through the work support; a feed bar in the plane of the needle with a portion aligned in the direction of feeding and extending forwardly of the needle, and a perpendicular terminal portion at its rear end immediately rearward of the needle in the direction of feeding; a rotary shaft at right angles to the feed bar with its axis substantially in the plane of the perpendicular portion of the bar; a rock shaft forward of and parallel to the rotary shaft and oscillated therefrom; a rocker on the rock shaft connected to the front end of the feed bar to impart longitudinal feeding movements to the bar; a rotary actuator on the rotary shaft; a link connecting the rotary actuator with the perpendicular portion of the feed bar to impart lift movements to said bar; and means cooperative with the needle in stitch formation including a looper which moves in an orbit at the needle or work support side of the feed bar, and a carrier arm for the looper movable laterally of the feed bar at the side thereof remote from the work support.

3. In a sewing machine, a work support; a reciprocating needle operated from one side of the work support; a rotary shaft extending lengthwise of the other side of the work support; means adjacent one end of the shaft for driving it; a feed bar aligned in the direction of feeding in the plane of the needle and extending forwardly of the needle; a rock shaft parallel to the rotary shaft at the same side of the work support; an actuating connection between the drive

end of the rotary shaft and the corresponding end of the rock shaft for oscillating the latter; a rocker at the opposite end of the rock shaft connected to the feed bar to communicate longitudinal feed movements thereto; and means cooperative with the needle in stitch formation including a looper which moves in an orbit at the needle or work support side of the feed bar, and a carrier arm for the looper movable laterally of the feed bar at the side thereof remote from the work support.

4. In a sewing machine, a frame with a hollow base affording a work support, and a standard extending perpendicularly therefrom at one end and supporting a parallel needle arm; a needle guided for reciprocation at the front end of said arm; a needle-actuating shaft extending lengthwise of the needle arm; a shaft extending lengthwise of the base rearwardly of the needle with respect to the direction of feeding; gearing within the standard connecting the two shafts at one end; a rock shaft within the base parallel to and substantially coextensive with the second shaft; connections by which the rock shaft is oscillated from the drive end of the said second shaft; a feed dog; a supporting bar therefor aligned in the direction of feeding in the plane of the needle and extending forwardly of the needle; a rocker at the opposite end of the rock shaft connected to the front end of the feed bar forwardly of the needle for imparting longitudinal feed movements to the feed dog; and means cooperative with the needle in stitch formation including a looper which moves in an orbit at the needle or work support side of the feed bar, and a carrier arm for the looper movable laterally of the feed bar at the side thereof remote from the work support.

5. In a sewing machine, a frame with a hollow base, a hollow standard extending perpendicularly therefrom at one end and supporting a parallel needle arm, partitions crosswise of the base in continuation of the opposite walls of the standard, and an isolated chamber beyond the outer partition; a reciprocating needle at the free end of the arm; a needle-actuating shaft extending lengthwise of the needle arm; a horizontal shaft extending lengthwise within the base, the latter shaft extending through the partitions with its rear end terminating in the chamber aforesaid; gearing within the standard connecting the two shafts; a rock shaft within the base parallel to and substantially co-extensive with the lower shaft, said rock shaft being forward of the needle with respect to the direction of feeding; connections within the chamber aforesaid by which the rock shaft is oscillated from the lower shaft; a rocker on the rock shaft at its distal end; a feed dog; a feed dog carrier bar in the plane of the needle connected to the rocker for imparting longitudinal feed movements to the feed dog, said bar being aligned in the direction of feeding; a looper to cooperate with the needle and movable transversely of one side of the feed bar; and a carrier for the looper movable transversely of the opposite side of the feed bar.

6. A sewing machine according to claim 5, in which the isolated chamber is provided with a retractable cover so that access may be had to the rock shaft oscillating means housed within said chamber.

7. In a sewing machine for chain-stitching articles successively passed through it, a reciprocating needle; a feed bar extending forwardly of the needle with regard to the direction of feeding and lying in the plane of the needle, and

having a perpendicular terminal portion at its rear end immediately rearward of the needle; means connected to the front end of the feed bar forwardly of the needle for imparting longitudinal feed movements thereto; means connected to the perpendicular portion of the bar for imparting lift movements thereto; a looper to cooperate with the needle in stitch formation; and means for severing connecting portions of the stitch chain between successive articles including a cutting instrumentality which is operative in a plane parallel to and immediately rearward of the perpendicular terminal portion of the feed bar.

8. In a sewing machine, a reciprocating needle; a feed bar having a portion aligned in the direction of feeding and extending forwardly of the needle and with provision for clearance of the needle, and a perpendicular portion at its rear end; a rotary shaft at right angles to the feed bar with its axis substantially in the plane of the perpendicular portion of the bar; a rock shaft extending parallel to the rotary shaft and oscillated therefrom; a rocker on the rock shaft connected to the front end of the feed bar to impart longitudinal feed movements to said bar; a rotary actuator on the rotary shaft; a link connecting the rotary actuator with the end of the perpendicular portion of the feed bar to impart lift movements to the latter; a looper to cooperate with the needle in stitch formation; means for supplying continuous reinforcing tape for attachment to articles by the stitching; and mechanism for severing the connecting chain and the tape between the successive articles including cutting means operative in a plane parallel to and immediately rearward of the perpendicular portion of the feed bar.

9. In a sewing machine for chain-stitching articles successively passed through it, a frame with a hollow base having a hollow standard extending perpendicular thereto at one end and supporting a needle arm in parallel relation to the base; a needle-actuating shaft extending lengthwise of the needle arm; a rotary shaft extending lengthwise within the base; gearing within the standard connecting the two shafts; a rock shaft within the base parallel to and substantially co-extensive with the rotary shaft; housed connections whereby the rock shaft is oscillated from the drive end of the rotary shaft; an arm at the opposite end of the rock shaft; a feed dog; a carrier for the feed dog extending forwardly of the needle with respect to the direction of feeding and connected at its front end to the arm

5 for imparting longitudinal feed movements to the feed dog; severing mechanism including cutting means within the base rearward of the feed bar; and a rearwardly open slot in the base at the rear thereof through which the portions of the stitch chain connecting successive articles drop into the province of the cutting means.

10 10. In a sewing machine for chain-stitching articles successively passed through it, a frame with a hollow base; a rotary shaft extending lengthwise through the base; means at one end of the shaft for driving it; a reciprocating needle movable into the base; a feed bar having a portion aligned in the direction of feeding and extending forwardly of the needle with provision for clearance of said needle, and having a perpendicular portion at its rear end; a rocker connected to the front end of the feed bar whereby longitudinal feed movements are imparted to said bar; a rotary actuator on the distal end of the shaft; a link connecting the rotary actuator to the end of the perpendicular portion of the feed bar and extending substantially parallel to said portion for imparting lift movements to the feed bar; a looper to cooperate with the needle in stitch formation; and mechanism for severing connecting portions of the stitch chain between the successive articles including a cutting element and a support therefor located in the base 20 in an interval between the rear wall of the latter and the perpendicular end portion of the feed bar.

15 25 30 35 40 45 50 55 11. In a sewing machine, a reciprocating needle; a feed bar extending forwardly of the needle in the line of feed to actuating means therefor; a feed dog in the form of a cantilever carried by and overhanging the bar at the stitch point of the machine, with provision of a clearance interval between said dog and said bar; and a looper movable through said interval to cooperate with the needle in stitch formation.

12. In a sewing machine, a reciprocating needle; a feed bar extending forwardly of the needle in the line of feed to actuating means therefor, and having an aperture through which the needle passes; a feed dog in the form of a bifurcated cantilever carried by and overhanging the bar at the stitch point of the machine, with provision of a clearance interval between said dog and said bar, the side portions of said dog extending at right angles to the needle at opposite sides thereof; and a looper movable through said interval to cooperate with the needle in stitch formation.

GEORGE SAUER.
